(57) **CLAIM**

The ornamental design for a loader arm for a work vehicle, as shown and described.

DESCRIPTION

FIG. 1 is a perspective view of a loader arm for a work vehicle according to an exemplary embodiment of the present subject matter.

FIG. 2 is a first side view of the loader arm illustrated in FIG. 1.

FIG. 3 is a second side view of the loader arm illustrated in FIG. 1.

FIG. 4 is a first end view of the loader arm illustrated in FIG. 1.

FIG. 5 is a second end view of the loader arm illustrated in FIG. 1.

FIG. 6 is a top view of the loader arm illustrated in FIG. 1.

FIG. 7 is a bottom view of the loader arm illustrated in FIG. 1; and,

FIG. 8 is another perspective view of the loader arm illustrated in FIG. 1, particularly illustrating an environmental view of the loader arm installed on a work vehicle, such as a wheel loader.

The broken lines contained within the figures, including, but, not limited to, any dash-dot broken lines and/or dash-dot-dot broken lines, represent portions of the loader arm for a work vehicle that form no part of the claimed design. Additionally, contour lines and/or surface shading are illustrated simply for purposes of highlighting the solid-rendering, and, thus, form no part of the claimed design.

1 Claim, 5 Drawing Sheets
